UNITED STATES PATENT OFFICE.

WALTER J. COLVIN AND LOUIS KIRSCHBRAUN, OF OMAHA, NEBRASKA.

SEAL FOR CAR DOORS.

Application filed March 6, 1925. Serial No. 13,443.

This invention relates to improvements in seals for car doors, and refers more particularly to improvements in a device for sealing the locks of freight car doors.

5 In its specific embodiment, the present invention contemplates the use of a breakable closure plaque which is inserted in place to seal the lock after the car door has been closed and locked. The breakable plaque 10 must be fractured to allow the removal of the bolt and unlocking of the door.

Goods valued at many thousands of dollars, are stolen annually from freight cars by thieves who have become expert in tampering with the present styles of seals, without leaving any evidence to indicate that the seal had been broken. This results in disagreements between shippers, consignees and transportation companies as to whom should 20 bear the loss.

The device of the present invention cannot be tampered with, nor the plaque removed without fracturing same, indicating immediately that the seal has been broken. Various 25 advantages and objects will appear from the following description.

In the drawings:

Fig. 1 is a face view illustrating the invention in use with one kind of lock.

30 Figs. 2 and 3 are cross sectional views taken respectively on lines 2-2 and 3-3 of Fig. 1. Fig. 4 is a face view illustrating the invention in use with a style of lock different from that shown in Fig. 1. Fig. 5 is a cross sectional view taken on line 5-5 of Fig. 4.

Referring in detail to the drawings, 1 designates the door of a railway freight car having the eye bolt 2 in which the chain 3 40 is anchored. The other end of this chain 3 is connected with a freely swinging locking bolt 4, which latter is apertured or slotted immediately adjacent its extremity as shown at 5. The seal designated as a whole at 6 45 comprises a retaining case or block 7 having flanges or extensions 8 through which the bolts 9 extend, said bolts being secured in the door or frame 10 of the freight car. The block 7 may be of metal, wood or other suitable non-flexible material and is provided on its upper face with the inwardly projecting integral lip 11, which latter preferably closes three sides of the block 7 which may be rectangular in shape, if desired, as shown, the

purpose being to leave one open end to permit the insertion of the closure plaque 12.

The closure plaque 12 is made of brittle material such as glass, clay, tile or other ceramic flat plate or analogous material capable of being readily fractured. The front 60 portion of the closure plaque 12 may be slightly tapered on its under surface as shown at 13 to facilitate the insertion of the plate over the spring tensioned locking stud 14 held by the spring 15. This locking stud 65 14 is adapted to register with a recess or aperture in the lower surface of the closure plaque as shown clearly in Figs. 2 and 5. Fixed in the case 7 and projecting from the surface thereof is the pin 16 adapted to register with the aperture 5 in the locking bolt 4. An enlarged recessed portion 17 surrounds the pin 16.

The operation of the device will be apparent from the foregoing description. In 75 sealing a car, the case 7 of course, being in place, the aperture 5 of locking bolt 4 is placed in registration with the projecting pin 16, as shown clearly in Figs. 2 and 5, the top of said bolt lying substantially flush with 80 the upper surface of case 7, the body of the bolt lying in the recess 17. The closure plaque 12 is then slid over the spring tensioned locking stud 14 until the recess, heretofore described, on the lower surface of the plaque, registers with said stud. The lock 85 is then sealed and the locking bolt 4 cannot be removed from its locked position unless it is raised above the pin 16, or, in other words, in the direction of the closure plate. 90

The only way in which the closure plate can be removed is to fracture same which destroys the seal. It is understood of course, that every car is sealed with a distinctive number, which, in the present instance, may be engraved, stamped or otherwise permanently embossed or applied to the sealing plaque in such a way that it cannot be readily imitated or changed. Thus the fracturing of the plaque indicates immediately that 100 the seal has been broken. The lips 11 on the retaining case or structure 7 can be heavy enough and constructed of such material as cast iron, certain bronzes and the like, that they will break more or less instantly if forced upward, and will not yield to any bending strains. The locking bolt 4 may be flat or rounded. It will be readily seen that 105

the device of the present invention is absolutely foolproof.

Referring more particularly to Figs. 4 and 5, the seal is shown in use with a lock of the hasp type. The fixed bracket 18 on the side 19 of the car is bifurcated at 20 to receive the end 21 of the hasp 22 on movable door 23. The bracket 18 and hasp 22 are apertured on their ends as shown at 24 to receive the bolt 4. It is understood, of course, that the seal may be positioned above or below the hasp.

We claim as our invention:

1. In a car door seal, the combination with 15 a retaining case having a plaque retaining means on its exposed surface and adapted to be attached to a car, a slot in said exposed surface, a pin projecting from the surface of the slot, a separate spring tensioned 20 locking stud mounted in and projecting from the surface of said case, an apertured locking bolt adapted to be placed in said slot, the aperture registering with said pin, a breakable closure plaque having an interior recess 25 inserted in said plaque retaining means, said

interior recess being adapted to register with said spring tensioned locking stud to hold the plaque in locked position.

2. In a car door seal, the combination with 30 a case of non-flexible material adapted to be attached to a freight car and having a retaining lip projecting upwardly and inwardly around the major portion of the upper surface thereof leaving a free space, of a recess in the surface of said case, projecting means in said recess adapted to register with an apertured locking bolt placed in said recess, a tensioned locking element projecting from the surface of said case, a breakable closure plaque having a recess in its lower face inserted in the free space and held beneath the retaining lip, said recess registering with the tensioned locking element to secure same in locked position, said plaque retaining the bolt in place, releasable only in the direction of the closure plaque when the latter has been fractured.

WALTER J. COLVIN.
LOUIS KIRSCHBRAUN.
